ATTORNEYS.

UNITED STATES PATENT OFFICE.

ALFRED H. HUMPHREY, OF NEW YORK, N. Y., ASSIGNOR TO GENERAL GAS LIGHT COMPANY, OF KALAMAZOO, MICHIGAN.

GAS-HEATER.

1,373,429.

Specification of Letters Patent.

Patented Apr. 5, 1921.

Application filed May 2, 1918. Serial No. 231,991.

To all whom it may concern:

Be it known that I, ALFRED H. HUMPHREY, a citizen of the United States, residing at the city, county, and State of New York, have invented certain new and useful Improvements in Gas-Heaters, of which the following is a specification.

This invention relates to improvements in gas heaters.

10 My improved gas heater is especially designed by me for use in fireplaces and I have illustrated the same in that relation although desirable for use in other relations.

The main objects of this invention are:

15 First, to provide an improved gas heater which is very efficient in the matter of heat radiation.

Second, to provide an improved gas heater adapted for use in connection with a fireplace in which the products of combustion are effectively discharged or delivered to the fireplace flue.

20 Third, to provide an improved gas heater in which a large percentage of the heat units is delivered as radiant heat in a highly effective manner.

Fourth, to provide in a gas heater an improved radiant.

Further objects, and objects relating to 30 structural details, will definitely appear from the detailed description to follow.

I accomplish the objects of my invention by the devices and means described in the following specification. The invention is 35 clearly defined and pointed out in the claims.

A structure which is a preferred embodiment of my invention is clearly illustrated in the accompanying drawing, forming a part of this specification, in which:

40 Figure I is a vertical section from front to rear of a gas heater embodying the features of my invention, a portion only of the fireplace being shown, and that conventionally.

45 Fig. II is a front elevation of my improved gas heater with the lower portion broken away.

Fig. III is a detail horizontal section on a line corresponding to line 3—3 of Fig. I.

50 In the drawing similar reference characters refer to similar parts throughout the several views, and the sectional views are taken looking in the direction of the little arrows at the ends of the section lines.

55 Referring to the drawing, 1 designates a

fireplace provided with a flue 2. My improved heater in the embodiment illustrated comprises a base 3 having rear legs 4 and andiron-like front legs 5. The base is provided with burner openings 6. The burners, 60 located below the base, are preferably those shown in my Patent #1245347, Nov. 6, 1917, and are disposed so that their tips are alined with the openings 6. The side walls are provided with posts or uprights 9. The 65 general structure and arrangement of these parts is substantially that shown in my Letters Patent No. 1,280,740, dated October 8, 1918.

I mount a fireback 10 upon the base, the 70 fireback having a forwardly inclined fluted face 11 with an overhang 12 at the top of the face. The top 13 of the fireback projects substantially above the overhang 12 and is of substantial body, the same being rearwardly inclined and preferably outwardly 75 curved, as shown in the drawing.

The radiants 14 are arranged on the base over the openings 6 and against the face of the fireback. These radiants are tubular 80 with foraminated walls and the front and rear walls converge toward the top. The rear walls of the radiants are forwardly inclined to correspond to the forward inclination of the face of the fireback. The 85 front walls of the radiants are also preferably forwardly inclined, the inclination, however, being substantially less than that of the rear walls, so that the front and rear walls of the radiants converge upwardly as 90 stated. The upper ends of these radiants are under but adjacent to the overhang 12. The radiants preferably have inwardly projecting spurs or fingers 15 on their front and rear walls which project into the radiants so that the products of combustion passing upwardly therethrough are brought into effective contact therewith increasing the heating capacity of the radiants and the 95 heat units absorbed from the products of combustion. These spurs are preferably staggered or alternately arranged as shown.

By forwardly inclining the fireback as illustrated and the rear wall of the radiants to correspond therewith the products of combustion impinge on the rear walls of the radiants and are reflected more or less against the front walls thereof and, owing to the converging relation of the walls, this is continued well to the top, so that the 110

radiants become incandescent for substantially their full length. The fireback becomes heated and the heat radiates forwardly therefrom in a very effective manner. The overhang and the inclined face of the fireback both serve to effectively direct the heat forwardly into the room well toward the floor.

In use the rearwardly inclined portion of the top of the fireback becomes heated and this induces a backward current in the products of combustion, so that they are discharged to the flue 2 instead of being discharged upwardly and forwardly into the room as I have found to be the case in other structures even when positioned within a fireplace having a flue. Some fireplaces are "dummies" or without flues, and my improvements are desirable for use in such relation as they prevent the discoloring and scorching of the mantel.

My improved heater may be positioned in front of a fireplace instead of within the same and still the products of combustion will be effectively discharged into the fireplace owing to the back draft or back current in the products of combustion.

My improved gas heater is highly efficient in that it radiates a large proportion of the heat units.

I have illustrated and described my improvements in an embodiment which I find very practical. I have not attempted to illustrate certain modifications and adaptations which I have made as I believe the disclosures made will enable those skilled in the art to which my invention relates to embody or adapt the same as may be desired or circumstances dictate.

Having thus described my invention, what I claim as new and desire to secure by Letters Patent, is:

1. In a structure of the class described, the combination with a fireplace, of a gas heater disposed therein comprising a fire-

back of earthy material having a forwardly inclined face with an overhang at its top, the top of the fireback projecting substantially above such overhang and being of substantial body and rearwardly inclined so that in use it becomes heated and produces a back draft current in the products of combustion above the fire back, tubular foraminated radiating elements disposed with their upper ends below but adjacent to said overhang of said fireback, and burners disposed below said radiating elements.

2. A gas heater comprising a fireback of earthy material having a forwardly inclined face with an overhang at its top, the top of the fireback projecting substantially above such overhang and being of substantial body so that in use it becomes heated and produces a back draft current in the products of combustion above the fireback, tubular foraminated radiating elements disposed with their upper ends below but adjacent to said overhang of said fireback, and burners disposed below said radiating elements.

3. In a gas heater, the combination of a base, a fireback of earthy material arranged on said base and having a forwardly inclined fluted face with an overhang at the top of its face, foraminated tubular radiating elements disposed on said base with their upper ends below but adjacent to said overhang of said fireback and having converging forwardly inclined front and rear walls, the inclination of the rear wall being substantially that of the fireback, the front wall having a substantially less inclination, and burners disposed below said radiating elements.

In witness whereof I have hereunto set my hand and seal in the presence of two witnesses.

ALFRED H. HUMPHREY. [L.S.]
